REELING DEVICE FOR TAG FORMING
MACHINES

Hans Irmischer, New York, N. Y., assignor to
Millie Patent Holding Co. Inc., New York, N. Y.,
a corporation of New York

Original application August 29, 1931, Serial No.
560,082, now Patent No. 1,951,417, dated March
20, 1934. Divided and this application May 12,
1932, Serial No. 610,814

1 Claim. (Cl. 242—158)

This application is a division of applicant's co-pending application Ser. No. 560,082 for Tag forming machine filed August 29, 1931, now Patent No. 1,951,417, issued March 20, 1934.

5 The present invention relates to devices for forming tags and providing the same with means whereby they may be attached to suitable articles and embodies, more specifically, an improved device for forming tags and securing the same in spaced relation upon a continuous supply of string or other flexible means by which the tags may be attached to suitable articles.

More particularly, the invention embodies a device for forming and securing tags successively 15 to a continuous string or the like and winding the same uniformly upon a suitable reel. The invention is particularly useful in connection with the forming of tags to be secured to tea balls, such tags bearing the label, brand or other indicia 20 suitable for designating the source of origin, brand, etc. In this connection, it should be noted that where the tags are secured in spaced relation upon a string or other flexible means, it is necessary that the winding of the string upon 25 reels take place without disturbing the spaced relationship of the tags, the position of such tags being preserved in order that upon subsequent securing operations of the tags to the desired articles, the tags may not become entangled.

30 In the operations necessary to form tea bags or other similar articles, the bag, after being formed, has secured thereto a string upon which a label has been secured in order that each individual bag may have its proper label. Suitable 35 continuous tapes are provided with the desired indicia, upon either or both sides thereof and the printed tapes are supplied to a device in order that portions of suitable design, bearing the previously printed indicia, may be stamped from 40 the tapes. Simultaneously with the stamping operation, a wire staple is formed and inserted through the successive labels, the upsetting of the staple taking place subsequent to the securing of a string or other attaching device under the 45 staple. After such operation has taken place, the string to which the labels are attached successively is carried to a reel and wound thereon in accordance with the rate of securing of the labels to the string.

50 In effecting the foregoing operations, it is necessary that an effective string winding and take-up mechanism may be provided to insure the continuous and proper winding of the string upon reels.

55 An object of the invention, accordingly, is to

provide a device for forming tags from a continuous supply of tape and stapling the same successively to a continuous supply of string or other suitable attaching means, the device including an improved take-up mechanism for the string to 5 which the tags have been stapled.

A further object of the invention is to provide a device of the above character, wherein the foregoing take-up mechanism for the string to which the tags have been stapled includes a substantially continuously operating drive from 10 which power is taken to actuate a reel supporting spindle in such fashion that the movement of the reel is interrupted for only comparatively short intervals of time, during which time the tags are 15 stapled thereto.

A further object of the invention is to provide an improved reel mounting and actuating means whereby axial movement of the reel is effected in addition to rotation thereof upon its own axle 20 in a predetermined manner, this means including an axial feed mechanism, wherein the position of the reel with respect to the axial feed mechanism may be varied with facility.

Further objects, not specifically enumerated 25 above, will be apparent as the invention is described in greater detail in connection with the accompanying drawings, wherein:

Figure 1 is a plan view of a machine for forming tags and securing the same successively and 30 in uniform spaced relationship upon a string or other attaching means.

Figure 2 is a view in side elevation showing the machine of Figure 1.

Figure 3 is a view in side elevation, showing the 35 driving mechanism for the reel, constructed in accordance with the present invention.

Figure 4 is a view in section, taken on the dot and dash lines of Figure 3, and looking in the direction of the arrows 4—4.

Figure 5 is a view in section, taken on the dot and dash line of Figure 3, and looking in the direction of the arrows 5—5 thereof.

Figure 6 is a plan view showing the feeding mechanism for moving the reel axially.

Figure 7 is a view in end elevation showing the split nut and connection between the feed mechanism and the reel.

Figure 8 is a top plan view partly broken away showing the reel with its driving mechanism in 50 assembled relation. Figure 9 is a cross sectional view on line 9—9 of Figure 8.

With reference to Figures 1 and 2, a frame of a machine constructed in accordance with the present invention is indicated at 1 and is formed 55

with a horizontal table 2 having a lateral extension 3. A shaft 4 is journaled upon arms 5 formed upon the frame and any suitable means is provided for supplying power to the shaft. In the 5 construction shown, a driven sprocket 6 is secured to the shaft 4 and receives power from a suitable source through a chain connection.

The extension 3 of the table serves as a support for the tape 7 which is supplied continuously from 10 a suitable source and has, at spaced intervals thereon, suitable printed matter. The feeding mechanism for advancing the tape through the machine comprises a crank arm 8 which is journaled upon a bracket 9, secured to the extension 15 3 and connected to the link 10 through a suitable adjustable connection 11. The link 10 is driven by an arm 12 which is eccentrically mounted upon the driving shaft 4, rotation of the shaft thus causing reciprocation of link 10. Upon the other 20 end of the bell crank lever 8, a link 13 is pivoted, the other end of the link being journaled at 14 upon a slidably mounted head 15. The head 15 is slidably mounted upon a guide 16 which is carried by the extension 3 and is thus adapted to reciprocate in response to the reciprocating movement of link 10.

Upon the slide 15, a dog 17 is mounted, the dog being normally urged into engagement with the slide by means of a spring 18 and maintained in 30 proper position with respect thereto by means of a link 19. The tape 7 is formed with spaced perforations 7' which are adapted to be engaged by the dog 17 and thus movement of the tape is effected during movement of the slide 15 toward 35 the table 2 since, during such movement, the dog 17 engages the apertures 7'.

The tape 7 is moved across a punch anvil 20 and, during movement of the dog 17 and slide 15 away from the table 2 (the tape at this time remaining stationary), the stamping or punching 40 operation takes place. After the tape has had the tags stamped therefrom, the remaining portions thereof are wound upon a suitable take-up reel.

A head 23 is mounted upon guides 22, a punch 45 24 being secured to the head. Reciprocating motion is imparted to the head and punch by means of a connecting rod 25 which is mounted upon an eccentric 26, carried by the shaft 4. The movement of the punch 24 and dog 17 is synchronized 50 in such fashion that the punch advances into the tape carried by the punch anvil 20 upon movement of the dog 17 away from the table 2. In this fashion, the tape 7 remains stationary while being punched.

Simultaneously with the punching operation described above, a staple is formed and secured 55 to the tag which has been punched, the staple simultaneously securing the tag to a continuous string which is wound upon a reel 125 in a manner which will be described presently. The tag forming and stapling operations are described in detail in the copending application No. 360,082 of which the present application is a division.

After the stapling of the tags successively to 60 the string 67, the latter is wound upon a suitable reel 125 carried by a reel spindle 70. The reel spindle 70 comprises a tube which is mounted upon a stationary rod 71, shown in Figures 3 and 4. The stationary rod 71 is secured to an extension 72 of the frame of the machine 1, as indicated 65 at 73. The spindle or sleeve 70 is secured to a gear 74 which has mutilated portions 75 spaced about the periphery thereof. Gear 74 is engaged 70 by a driving pinion 76 which also has a mutilated

portion 77 adapted to cooperate with the spaced mutilated portions 75 of the gear 74. Pinion 76 is mounted upon a shaft section 79 which is journaled at 78 upon the extension 72 and at 80 in a bracket carried by the extension. Rotation is 5 imparted to the shaft section through a universal joint 81 and shaft 82 which receives power from a universal joint 83 and bearing 84 upon which a driving sprocket 85 is secured. Driving sprocket 85 may be driven from a countershaft upon 10 which a primary driving sprocket 86 is secured, this driving sprocket receiving power from the power shaft 4 in any suitable fashion. It will thus be seen that rotation of the shaft section 15 79 causes the spindle 70 to be rotated during the 18 engagement of the teeth of driving pinion 76 with the teeth of the gear 74. As the mutilated segment 77 of the driving pinion engages the mutilated portion 75 of driving gear 74, rotation of the spindle 70 and the reel carried thereby is 20 temporarily halted and the interval of time during which the rotation of the reel ceases is the time during which the punch 24 advances into the tape 7 and punches a tag therefrom and the stapling mechanism secures the tag to the string. 25

Axial movement is imparted to the reel by means of a suitable feed screw 87, the lower extremity of which carries a driving gear 88 which is engaged through gear 88' upon the shaft of a planetary pinion 89 carried by a head 90 which 30 is mounted upon the spindle 70 (Figure 5). Planetary pinion 89 engages internal teeth 91 which are formed in an annular head 92 and thus, as the spindle 70 rotates, the feed screw 87 is turned to move a feed head 93 axially of the 35 spindle. The take-up reel for the string preferably engages the head 93 and thus moves axially of the spindle as the string is wound thereon.

The feed head 93 is preferably formed of spaced 40 members 94 having bifurcated extensions 95 45 which engage the spindle 70 to prevent rotation of the head with respect to the feed screw 87 (Figures 6 and 7). Between the members 94, cooperating nut sections 96 are pivoted, a spring 97 being provided to urge the sections normally together and into engagement with the shafts of the screws 87. Tags 98 extend upon opposite sides of the nut sections in order that pressure exerted thereon toward the members 94 may 50 separate the nut sections and effect disengagement of the nut from the feed screws. In this fashion, the head 93 may initially be adjusted to any desired axial position upon the feed screw 87.

It will thus be seen that a machine has been 55 provided which effectively winds a thread to which a plurality of tags have been secured in spaced relationship upon a reel, the mechanism being such as to synchronize the movement of the reel with respect to a tag forming and stapling 60 mechanism wherein the thread bearing the tags may be carried in a proper manner to the reeling mechanism. The reeling device is such as to feed the thread to which tags have been applied in spaced relationship to the reel, means being provided to advance the reel as it is wound whereby the thread may be carried upon the reel without becoming tangled. This operation is a substantially continuous one and affords a comparatively 65 smooth drive whereby violent shocks and excessive wear are eliminated.

While the invention has been described with specific reference to the accompanying drawings, it is not to be limited, save as defined in the appended claim.

I claim as my invention:

A reel mounting and feed controlling mechanism comprising a rotatable spindle, a driving gear secured to the spindle and formed with mutilated portions, a driving spindle engaging the gear and formed with a mutilated portion whereby

the spindle is rotated intermittently, a plate on the spindle, a feed screw journaled in the plate, means to impart rotation to the screw, a split reel positioning unit on the screw, and means to urge the split portions against the screw.

HANS IRMSCHER.
